UNITED STATES PATENT OFFICE.

WILLIAM E. BRADNER, OF NEWARK, NEW JERSEY, ASSIGNOR OF ONE-HALF TO A. KAUFMANN, OF NEW YORK, N. Y.

SHAWL-STRAP.

SPECIFICATION forming part of Letters Patent No. 269,509, dated December 26, 1882.

Application filed May 4, 1881. (No model.)

To all whom it may concern:

Be it known that I, WILLIAM E. BRADNER, of Newark, in the county of Essex and State of New Jersey, have invented a new and useful Improvement in Shawl-Straps, of which the following is a specification.

My invention relates to an improvement in shawl-straps wherein a web or strap is used by winding up to engage the package; and it consists in a rotating handle, on the ends of which the web is wound up; and in a pawl, ratchet, and spring, and in the construction and arrangement, substantially as herein set forth.

15 Figure 1 is a side elevation. Fig. 2 is a plan section of the frame. Fig. 3 is a cross-section of Fig. 1 on a line of *x x*. Figs. 4 and 5 are inside views of the ends of the frame, showing the relations of the ratchet, pawl, and spring. Figs. 6 and 7 are detailed views.

In my construction I provide for winding the web A up on the ends of the wooden handle B, the handle being hung in the frame C. The handle is provided at each end with a slit 25 or kerf, D, in which the two ends of the web are lapped and held by tacks T, driven through the wood and the ends of the web. On each end of the handle is placed a metal cap, E, having the feathers F, made to enter the end of 30 the kerf outside of the web, the feathers keeping the cap from turning except with the handle. The cap is cast with the ratchet G on the outside of it, coming, when in working position, against the ends H of the frame; and 35 to these ends, respectively, is pivoted a pawl, I, adapted to engage the ratchet to prevent the web from unwinding when needed to hold the package. The pawl is held against the ratchet by a spring, K, having one end attached to the pawl and the other to the end H, so that when the pawl is thrown up, as in Fig. 4, the spring presses it against the ratchet; but when it is thrown down, as in Fig. 5, in 40 passing the center of pressure the spring bears

the pawl down and keeps it out of the way or 45 out of contact with the ratchet when the web is being unwound to receive a package. The web passes through the slots L in the base of the frame C, which keep it in place.

In use the package is placed inside of the 50 webs, and the handle is turned, winding them up until the package is brought up in close contact with the under side of the frame, and held in a very convenient portable position.

I do not claim broadly a spring accomplishing the work of holding the pawl in and out of contact with the ratchet, for that in another 55 form may have been done.

I claim—

1. In a shawl-strap, the handle B, having 60 the kerfs D, adapted to receive the ends of the web A and feather F of the cap E, substantially as and for the purpose specified.

2. The cap E, having the recess adapting it to cover the split end of the handle B, and 65 having the feather F, fitted to enter the end of the kerfs D, and provided with the ratchet G, in combination with the handle B, substantially as and for the purpose set forth.

3. The combination of the handle B, having 70 the kerfs D, the cap E, provided with the feathers F and ratchet G, and the pawl I, substantially as and for purpose named.

4. In combination with the handle B, having the kerfs D, the web A, having the ends 75 secured in said kerfs, substantially as and for the purpose set forth.

5. In a shawl-strap, the combination of the handle provided with the ratchet G, and the frame H, carrying the pawl I and provided 80 with the curved spring K, one end of which is secured to the frame and the other to the pawl, substantially as and for the purpose set forth.

WILLIAM E. BRADNER.
